UNITED STATES PATENT OFFICE.

ISAAC MOORE, OF TORONTO, CANADA.

MANIFOLDING SALES-BOOK.

SPECIFICATION forming part of Letters Patent No. 635,796, dated October 31, 1899.

Application filed March 7, 1898. Serial No. 672,909. (No model.)

To all whom it may concern:

Be it known that I, ISAAC MOORE, manufacturer, of the city of Toronto, in the county of York, in the Province of Ontario, Canada, 5 have invented certain new and useful Improvements in Duplicating Check-Books, of which the following is a specification.

My invention relates to improvements in duplicating check-books; and the object of the 10 invention is to design a simple means in connection with the carbon-leaf holder whereby all the leaves of a stubless book or book comprising all originals and duplicates or triplicates may be held securely in place until the 15 last leaf is used; and it consists, essentially, of a carbon-leaf holder supported on arms in the cover and provided with a depending spike, which is designed to pass through several of the leaves at the head ends, so that 20 the leaves are securely retained in position during the continuous use of the book, the carbon-leaf holder and spike being spring-held in position, as hereinafter more particularly explained.

25 Figure 1 is a perspective view of a duplicating check-book and cover, showing my improvements. Fig. 2 is a longitudinal section through the book. Fig. 3 is a detail of the carbon-holder, showing the location of the retaining-spike. Fig. 4 is a detail of an alternative form of holding the carbon-leaf holder in position. Fig. 5 is a longitudinal section through Fig. 4. Fig. 6 is a perspective view of another alternative form.

30 In the drawings like letters and numerals of reference indicate corresponding parts in each figure.

A is the cover of the book, and A' a portion of the cover upon which my device is attached.

40 B B are two side bars having bent ends pivotally held in eyes b near the center of the cover. The free ends of the bars B B are enlarged and have connected to them the carbon-leaf holder, which consists of the flat bar C, provided with a rib c, soldered or otherwise secured to the enlarged ends of the bars B B.

45 C' is a flap provided with depending flanges c'. The flap C' is pivoted on pins c² in the enlarged ends of the side bars B B. When 50 swung, the flanges c' are designed to fit over the rib c and grasp the carbon leaf 2, which

is placed over the rib, and this securely holds such carbon leaf in position.

c³ is an opening through which depends a spike D, secured in the rib c, and having a 55 bent pointed end d.

In Fig. 1 I show the form of book E which is known as a "continuous" book, the original and duplicate leaves being continuously connected together by dotted lines and folded 60 backward and forward, the head ends, on which the name of the merchant is printed, being held in position by the spike, as indicated particularly in Fig. 2. In order to hold the spike and carbon-leaf holder down in position, I provide an elastic band F, which is passed over the carbon-leaf holder, around the book and cover, through a loop f on one side, and attached to the enlarged end of the side bars B B. I can also in this form of book 65 70 provide a side carbon leaf 3 and holder 4 of any particular design, which is adapted to be thrown over across the tablet when used, as is well understood.

In Figs. 4 and 5 I show an alternative form 75 in which the side bars B' of the carbon-leaf holder are secured to a central plate B² at one end, while the opposite ends have extensions b' from the carbon-leaf holder C C', which extend into jaws f' on the end of the compression-spring F', which is secured in the center 80 by a rivet f² to the cover. The cover A A is turned up also at A². The spike D in this instance is exactly similarly arranged to that shown in Fig. 2. (See Fig. 5.) The carbon- 85 leaf holder may be raised by catching hold of the side bars near the spring until the extensions b' pass out of the jaws f'. To insert the extensions b' into place in the jaws f' again, it is simply necessary to raise the spring 90 F' to the desired height. It will thus be seen that the main body of leaves or book-leaves may be held in position.

In Fig. 6 I show the carbon-leaf holder C' secured on the bent end of a spring-arm G, 95 which is fastened to the cover by staples g, near the bottom of the leaf. The normal tendency of the spring-arm G is to throw the carbon-leaf holder C' upwardly. The spike D is also identically arranged to that shown 100 in the preceding figures. In order to hold the carbon-leaf holder and spike down, so that

such spike will extend into the leaves at the head end, I provide a hook H, which has a longitudinal movement upon a wire rod I, secured to the bottom of the covering. By 5 throwing the hook toward the carbon-leaf holder it is held down very securely, so that the spike extends into the leaves. By throwing it in the opposite direction the spring-arm G will throw the carbon-leaf holder upwardly, and the book may be removed or a new one 10 may be inserted, as the case may be.

It will thus be seen that I am enabled by my device, particularly in the form shown in Fig. 1, to maintain the body of leaves in the 15 book securely in place during the manipulation of the book-leaves and carbon leaves.

Although I show my carbon leaf located at one end of the book, it will of course be understood that it might be located in the center of the book between the fly-leaf and duplicate or at any other point and when used in this way will hold the leaves just as firmly in 20 position.

What I claim as my invention is—

1. In a duplicating check-book, the combination with the cover and leaves, of an arm attached to the cover and provided with a carbon-leaf holder and a spike depending from the carbon-leaf holder, an elastic band passing around the book and over the carbon-leaf holder and a loop in the ends of the arms in which the elastic band is connected to the book as and for the purpose specified. 25

2. In a duplicating check-book, the combination with the cover and leaves, of the 30 arms, carbon-leaf holder secured in the free end of the arms and connecting the same together, the opening in the bottom plate of the holder and the spike having a turned bent end 35 designed to extend into one or more leaves of 40 the book as and for the purpose specified.

ISAAC MOORE.
